LATCH MEANS FOR HANDBAG FRAMES

David Karren, Brooklyn, N. Y.

Application May 9, 1936, Serial No. 78,844

12 Claims. (Cl. 292—83)

This invention relates to latch means for handbag frames and has for its general object and purpose to provide a novel and simply constructed latch means which may be easily and quickly operated to securely lock or hold the complementary frame members in closed position or release the same for relative opening movement, and which may be produced in a variety of ornamental attractive forms.

More particularly, it is an important object of the invention to provide a slidable latching member and means for mounting the same upon the top of one of the bag frame members for longitudinal movement, said latch slide having means to coact with the other bag frame member and hold said frame members in closed position, and means automatically acting at the end of the movement of the latch slide in one direction to release the same from latching engagement with the frame members and permit relative movement of the latter to their open positions.

More particularly, in a preferred embodiment of the invention, I mount the latch slide on a metal trim plate secured to the top of one of the frame members and overlying and concealing the tops of both frame members when they are in closed position, said trim plate having a free resiliently movable end portion, and cam means coacting with the latch slide when the latter is moved upon said end portion of the trim plate to displace said end portion of the trim plate and the latch slide relative to the frame members and release the latter for opening movement.

It is also an additional object of the invention to provide said trim plate at its opposite ends with suitable stops limiting movement of the latch slide in each direction, and said stops at the free end of the trim plate being constructed to coact with the two frame members and provide additional means for holding said frame members when in closed position against separation at one end of the frame.

With the above and other objects in view, the invention consists in the improved latch means for handbag frames and in the form, construction and relative arrangement of its several parts as will be hereinafter more fully described, illustrated in the accompanying drawing and subsequently incorporated in the subjoined claims.

In the drawing wherein I have disclosed one simple and practical embodiment of my invention, and in which similar reference characters designate corresponding parts throughout the several views:

Fig. 1 is a side elevation of one conventional type of handbag frame provided with my improved latch means.

Fig. 2 is an enlarged fragmentary side elevation showing the slidable latching member and the free end of the trim plate displaced from normal position to release the frame members.

Fig. 3 is a transverse sectional view taken on the line 3—3 of Fig. 1.

Fig. 4 is a similar sectional view taken on the line 4—4 of Fig. 2.

Fig. 5 is a top plan view and

Fig. 6 is a perspective view of a handbag provided with my novel latch means.

Referring in detail to the drawing, 5 and 6 respectively indicate the two relatively movable frame members hingedly connected with each other at their corresponding ends as indicated at 7. These frame members may be of any one of the several standard constructions now in general use, in which each frame member is provided with a continuous channel in which the upper and side edges of the bag or pouch material indicated at 8 are securely fixed. Each of these frame members has a continuous outer wall 25 or flange shown at 9.

A trim plate 10 extends longitudinally over the entire top of the frame member 5 and one end portion thereof is soldered, welded or otherwise securely fixed to the top flange of said frame member as indicated at 11. Preferably, this fixed or secured portion of the trim strip extends for somewhat more than one-third of the length of the frame member. The remaining portion of said trim strip or plate 10 is free or unattached 35 to the frame member and resiliently movable with respect to said frame member in the plane thereof. Preferably, the trim strip 10 is of such width that when the two bag frame members are in closed position, the edge portions of said trim strip project transversely beyond the respective frame members as clearly seen in Fig. 3 of the drawing, so that the tops of said frame members will be completely concealed.

Upon the trim plate 10 a latch member 12 is 45 slidably mounted. The longitudinal edges of the plate 10 are rounded or convex and the opposite edges of the latch slide 12 are formed with inwardly facing channels 13 which snugly receive said edges of the trim plate. This slide member 50 12 may be of various ornamental forms and one of the side flanges thereof extending beneath the plate 10 is formed with a downwardly turned fin or lip 14. However, this is not essential and, if desired, said fin or lip may be omitted.

To one end of the latch slide 12 a finger piece 15 of any desired ornamental form is pivotally connected and affords convenient means for sliding said member 12 longitudinally along the trim plate 10.

At its fixed end the trim plate 10 is provided with a suitable stop lug 16 projecting downwardly from said plate which limits the sliding movement of the member 12 in one direction.

10 At its other or free end the trim plate 10 on each of its side edges is formed with a downwardly and inwardly turned lug 17. These lugs in addition to acting as stops for limiting sliding movement of the member 12 in the opposite direction also extend over the edges of the flanges 9 of the two frame members when the latter are in closed position as seen in Fig. 1. Therefore, when the member 12 is in its latching position at one end of the frame, these lugs 17 will prevent relative separation of said frame members at their other ends.

15 Adjacent to the latter end of the frame member 5, an upwardly projecting cam lug 18 is fixed to the top wall thereof and protrudes through a slot or opening 19 in the trim plate 10.

20 From the above description, the operation of the device will be readily understood. When the latch member 12 is in the position seen in Fig. 1 of the drawing, the side flanges of said member beneath the trim plate 10 are disposed in the plane of the top flanges 9 of the frame members 5 and 6, while the lugs 17 at the free end of said trim plate also overlap the edges of said flanges. Thus, the two frame members are securely held in closed position. The fin or lip 14 affords additional security and is a precaution against possible separation of the frame members due to distortion or looseness in the hinge connections 7.

25 When it is desired to open the handbag, by means of the finger piece 15, the member 12 is moved to the left along the trim plate 10 and upon the free or unsecured section of said trim plate. When the end of slide 12 strikes the curved edge of the cam lug 18 and rides upwardly thereon, the unsecured section of the trim plate, together with slide 12, is forced or sprung upwardly from normal position in the manner illustrated in Fig. 2 of the drawing so that the side edges of the member 12 and the fin 14 will be positioned above the plane of the top flanges 9 of the two frame members and the lugs 17 on the end of the trim plate will also be positioned above these flanges. The two frame members 5 and 6 may then be relatively moved to their open positions as indicated in Fig. 4 of the drawing.

30 From the foregoing description considered in connection with the accompanying drawing, the construction, manner of use and the several advantages of my present invention will be clearly understood. It will be seen that the slide member 12 may be easily and quickly actuated to securely lock the two frame members in closed position or release the same for opening movement. The trim plate 10 in addition to its function as a part of the latching means provides an ornamental and attractive finish for the bag frame, while the slide member 12 and the finger piece 15 can also be produced in a great variety of novel and attractive designs. It will be seen that my new frame latching device requires no radical changes in the standard construction of such bag frames as heretofore used in the art. The device itself is of very simple and inexpensive construction, and the trim plate 10 and the cam

35 lug 18 can be readily attached to the bag frame member by simple mechanical operations.

I have disclosed herein a preferred mounting and arrangement of the trim plate and slide member 12 which has been found very satisfactory 5 in practical use. Nevertheless, it is to be understood that the essential features of my invention are susceptible of embodiment in various other alternative structural forms, and I accordingly reserve the privilege of resorting to all such legitimate changes in the form, construction and relative arrangement of the several parts as may be fairly comprehended within the spirit and scope 10 of the appended claims.

15 I claim:

1. In combination with a bag frame member, a latch member mounted upon the top of said frame member for longitudinal sliding movement and having a part to coact with a complementary frame member and retain the same in closed position relative to said first frame member, and means fixed to one frame member, and positively coacting with said latch member in its sliding movement in one direction, to move said latch member relative to the frame members and position 20 said part whereby the frame members may be relatively moved to open position.

2. In combination with a bag frame member, a latch member mounted upon the top of said frame member for longitudinal sliding movement 25 and having a part to coact with a complementary frame member and retain the same in closed position relative to the first frame member, and relatively stationary means carried by the first named frame member and positively coacting 30 with said latch member in its sliding movement in one direction to displace the same relative to the frame members whereby the latter may be moved to open position.

3. In combination with a bag frame member, a latch member mounted upon the top of said frame member for longitudinal sliding movement and having a part to coact with a complementary frame member and retain the same in closed position with respect to the first named frame member, a cam lug fixed to said first named frame member, and positively coacting with the latch member in its sliding movement in one direction to lift said latch member to an unlatching position and permit of the relative opening movement of the bag frame members.

4. In combination with a bag frame member, a latch member, means for mounting said latch member upon the top of the frame member for longitudinal sliding movement including a resiliently yieldable metal guide strip, said latch member having a part to coact with a complementary frame member and latch the same in closed position, and means fixed to the first frame member, coacting with said latch member at the end of its sliding movement in one direction, to angularly displace the same against the resistance of said yieldable metal strip and position said part to release the frame members for relative opening movement.

5. In combination with a bag frame member, a latch member, and means for mounting said latch member upon the top of the frame member for longitudinal sliding movement including means supporting the latch member at the end 60 of its sliding movement in one direction for angular displacement relative to the frame member and for returning the latch member to a normal position in parallel relation to the frame member, said latch member having a part to co-

act in the normal position of said member with a complementary frame member to retain the frame members in closed position, and relatively stationary means on the first named frame member coacting with said latch member at the end of its movement in one direction to angularly displace the same to frame releasing position.

5. In combination with a bag frame member, a metal trim strip extending longitudinally upon 10 the top of said frame member and having a part fixed thereto and a portion of said strip being resiliently movable in the plane of the frame member, a latch member slidable upon said trim strip having means to coact with a complementary frame member and retain the frame members in closed position, and means fixed to the 15 first frame member to coact with said slide member when the latter is moved upon the resiliently yieldable portion of the trim strip and angularly 20 displace said member against the resistance of said trim strip and release the bag frame members for opening movement.

6. In combination with a bag frame member, a metal trim strip extending longitudinally over 25 the top thereof and having an end portion fixed to said frame member, and an end portion resiliently movable in the plane of said member, a slide member longitudinally movable along said trim strip and having means for latching engagement with a complementary frame member, and a cam lug fixed to the first named frame member, and coacting with the latch member at the end of its sliding movement in one direction, to angularly displace the same to frame releasing 30 35 position against the resistance of the yieldable portion of said trim strip.

7. In combination with a bag frame member, a trim strip extending over the top of said frame member and fixed at one of its ends thereto, the 40 other end of said trim strip being resiliently yieldable in the plane of said frame member, a slide member longitudinally movable upon the trim strip and having means to coact with a complementary frame member and retain said 45 frame members in closed position, said trim strip at each of its ends having stop lugs limiting the sliding movement of said latch member, the stop lug at the yieldable end of said strip also adapted to coact with the complementary frame member 50 at one end thereof to hold the same against separation relative to the first named frame member, and means adapted to coact with the latch member when moved upon the yieldable end of the trim strip to angularly displace said member and 55 the end portion of the trim strip relative to the

first frame member and release the complementary frame member for movement to an open position.

9. In combination with a bag frame member, a metal trim strip mounted upon the top of said frame member and extending from end to end thereof, and said strip having an end portion resiliently yieldable in the plane of the frame member and provided with a terminal lug adapted to coact with one end of a complementary frame 10 member, when said trim strip is in normal position, to releasably latch the frame members against relative opening movement.

10. In combination with a bag frame member, a latch supporting element secured to the top of 15 said frame member and having a part movable with respect to the frame member, and a latch member movably mounted on said supporting element to coact with a complementary frame member, and retain the same in closed position 20 relative to said first named frame member, said latch member adapted to be moved upon said movable part of the supporting element for movement with the latter relative to said first named frame member to an unlatching position. 25

11. In combination with a bag frame member, a latch supporting element secured to the top of said frame member and having a resiliently yieldable part, movable with respect to the frame member in the plane thereof, and a latch member 30 movably mounted on said supporting element to coact with a complementary frame member and retain the same in closed position relative to said first named frame member, said latch member adapted to be moved upon said resiliently yieldable part of the supporting element for movement with the latter relative to said first named frame member to an unlatching position. 35

12. In combination with a bag frame member, a latch supporting element secured to the top of 40 said frame member and having a resiliently yieldable part, movable with respect to the frame member in the plane thereof, and a latch member 45 movably mounted on said supporting element to coact with a complementary frame member and retain the same in closed position relative to said first named frame member, said latch member adapted to be moved upon said resiliently yieldable part of the supporting element, and means, including said latch member, operative 50 in such movement of said latch member, to move said resiliently yieldable part of the supporting element and dispose the latch member thereon in unlatching position. 55

DAVID KARRON.
